UNITED STATES PATENT OFFICE.

CHARLES Y. KNIGHT, OF PASADENA, CALIFORNIA, ASSIGNOR TO KNIGHT AMERICAN PATENTS COMPANY, OF CHICAGO, ILLINOIS, A CORPORATION OF DELAWARE.

MULTIPLE PISTON.

Application filed October 6, 1922. Serial No. 592,911.

This invention relates to a multiple or two-part piston in which the exterior may be made of cast iron—to provide for the advantageous use of cast iron in contact with the cylinders in the ordinary use in internal combustion engines—and the interior made of a light weight material such as aluminum for example to provide a light weight even section piston construction with the advantages of providing for good cooling and rendering it possible to machine the skirt and head of the piston all over with the attending advantages flowing therefrom.

It is an object of the invention to construct a two-part piston of this character which may be easily assembled and which when assembled may be rigidly held in assembled position, the invention comprehending broadly the employment of a two-part light weight piston having the different parts constructed of different materials, such as those indicated.

Various other objects are within the scope of this invention such as relate to the arrangement of the related elements or the structure, and to various details of construction and to economies of manufacture and numerous other features as will be apparent from a consideration of the drawing and related description of a form of the invention, which may be preferred, in which—

Fig. 1 is a sectional view of one embodiment of the invention.

Fig. 2 is a similar view taken at right angles to the section of Fig. 1.

Fig. 3 is a sectional view similar to Fig. 1 showing a modification of the means of securing two parts of the piston together.

Fig. 4 is a similar view of a further modification.

Referring to Fig. 1, I have illustrated a cast iron exterior inverted shell part 1 which may be provided with a plurality of piston ring retaining grooves 2 and which may be of any desired thickness and may be machined exteriorly on the skirt 1 and the head 3 as heretofore referred to. The lower edge of the skirt 1 is provided with an interior ledge or retaining lip 4, for a purpose as will presently appear.

The interior part of the two-part piston is shown as an aluminum casting 8 provided with a head 9, a body portion 10 and a plurality of outward extending legs 11. The

under side of the top 3 of the piston exterior portion 1 is provided with a depending central portion or boss 3' and the head 9 of the aluminum interior part 8 is provided with a corresponding recess 12 which fits over the boss 3'. The head 3 is further provided at the central portion of the boss 3' with a screw-threaded opening 5 to receive a stud or bolt 13 screw-threaded therein to securely retain the aluminum interior portion 8 to the exterior cast iron portion 1 of the piston.

To form a secure locking means between the two parts the stud 13 may be screw-threaded to receive the castle nut 14 which, as will be apparent, will securely hold the two parts of the piston together at this point of contact, the locking pin 15 cooperating with the castle nut 14 to retain the same in assembled position. The aluminum interior portion 8 is provided at the body portion 10 thereof as shown in Fig. 2, with a transverse opening 17 to receive the wrist pin 18 for joining the piston to the connecting rod 20. It will be seen that the interior aluminum casting 8 is therefore provided with a central hollow portion 21 in the body portion 10 thereof in order to receive the end of the connecting rod 20 and permit proper operation of the parts in use.

The aluminum interior casting 8 is further retained in position by use of the legs 11 having the foot portions 22 which when the parts are assembled are adapted to spring over the ledge portion 4 at the bottom of the exterior skirt. It will be seen from Fig. 2 that the skirt 1 is provided with openings 24 through which the wrist pin 18 is inserted to assemble the piston to the connecting rod and a conventional type of joint between the wrist pin and connecting rod 20 is illustrated at 25.

In Fig. 3 it will be seen that the head 9 of the interior casting is secured over a depending boss 3' on the bottom side of the head 3 of the cast iron shell 1 without need of a bolt for securing the parts together at this point, it being apparent that the legs 11 when sprung in position place sufficient pressure on the parts to securely maintain the two-part piston assembled.

In Fig. 4 a further modification is illustrated in which the head 9 is recessed at 9' and provided with screw threads while the boss 3' is exteriorly screw threaded to receive the same. Otherwise the parts illustrated in

Figs. 3 and 4 correspond to those illustrated skirt, said inner portion being spaced from in 1 and 2. the upper portion of said skirt, and said lower connecting means being resilient.

It will be apparent that there will be many advantages flowing from the construction illustrated as one embodiment of the invention herein disclosed. A light weight piston is provided which at the same time makes possible the employment of a cast iron sleeve to contact with the cylinder walls in use, an advantage well known in the internal combustion engine art. At the same time the parts may be so proportioned as to render an even weight section of piston throughout which also has the advantages apparent to those skilled in the art.

It is apparent that, within the spirit of the invention modifications and different arrangements may be made other than as herein disclosed, and the present disclosure is illustrative merely, the invention comprehending all variations thereof.

I claim:

1. A two part piston comprising an outer integral part having a head and a skirt formed of a metal suitable for frictional engagement with a cylinder, and an inner part formed of light weight material provided with means for connecting a piston rod thereto, said inner part being protected from direct contact with hot combustion gases by said outer part and contacting with said outer part at spaced zones of contact, one of said zones of contact being at the head of the piston and the other adjacent the lower edge of the skirt, the lower portion of said inner part adjacent said last mentioned zone of contact being resilient, substantially the entire side walls of said outer part being free from contact with said inner part, and means for securing said parts together.

2. A two part piston comprising an outer part having a head and a skirt and an inner part provided with means for connecting a piston rod thereto, said inner part being secured to the head of said outer part and spaced from the upper portions of said skirt; means for securing said inner part to the outer part adjacent to the lower portions of the skirt; and means for automatically securing said inner part to said outer part adjacent the lower portion of the skirt when said inner part is inserted in said outer part.

3. In combination, a multiple part piston having an outer head and an integral skirt portion of a material suitable for frictional engagement with a cylinder and an interior portion for connecting the piston to the piston rod of relatively light weight material, said interior portion being protected from direct contact with hot combustion gases by said outer head and having a central bearing portion for the wrist pin of the connecting rod, and upper and lower connecting means for securing the inner portion to the head of said outer portion and the lower portion of said

4. In combination, a multiple part piston having an exterior head and skirt portion, a ledge on said skirt, an interior wrist pin bearing portion provided with a top to secure the same to said head of the exterior portion and a plurality of depending legs to engage said ledge on the skirt portion and arranged to operate with the upper contacting portions of said head and top to maintain the two portions of said piston in assembled position.

5. In combination, a multiple part piston having an outer portion with a skirt of a material suitable for frictional engagement with a cylinder and having a head and a ledge on the interior of the bottom of the skirt and an interior piston rod connecting portion of relatively light weight material having a wrist pin bearing and a head to join to the head of said skirt portion, and means to engage said ledge to maintain said multiple part piston in assembled relation.

6. In combination, a multiple part piston having a skirt portion of a material suitable for frictional engagement with a cylinder, having a head and a ledge on the interior of the bottom of the skirt and an interior piston rod connecting portion having a wrist pin bearing and a head to join the head of said skirt portion, provided with inter-engaging screw-threaded means for securing the head of the exterior and head of the interior portions together.

7. In a piston having a skirt an interior piston part of relatively light weight material having a top portion adapted to engage the under side of the top of the piston so as to be protected from direct contact with hot combustion gases, and a central hollow portion providing oppositely aligned spaced bearings for the wrist pin of the piston and rod, the hollow portion of said central body part being arranged to receive the connecting rod, said central hollow portion being spaced from the piston skirt and resiliently contacting therewith solely at the bottom edge thereof.

8. An interior piston part of relatively light weight material having a top portion, a hollow body portion provided with spaced aligned bearings for the wrist pin and a plurality of retaining legs flaring outwardly to engage the lower portion of the skirt of the piston, said legs being spaced on opposite sides of the path of movement of the connecting rod in operation.

9. A two part piston comprising an outer part having a head provided with a central inwardly extending boss and a skirt, an inner part having a socket receiving said boss and secured thereto, said inner part being spaced from the skirt of said outer part except at points adjacent the lower edge thereof at

which points said inner part is secured to said outer part.

10. A two part piston comprising an outer part having a head and a skirt, said head having a central inwardly extending boss, an outer part having a socket receiving said boss and provided with downwardly extending legs, said skirt having an inwardly projecting ledge adjacent its lower edge which is engaged by said legs, and means for securing said inner part to the head of said outer part. 15

11. A two part piston comprising an outer part having a head and a skirt provided with

an inwardly extending ledge adjacent its lower edge, an inner part having a portion engaging the head of said outer part for centralizing the parts with respect to each other, aligned bearings for receiving a wrist pin, and a pair of downwardly extending legs 20 adapted to engage said ledge at diametrically opposite points located in a plane at right angles to a plane containing the axis of said bearing, and means for securing said parts together. 25

In testimony whereof, I affix my signature.

CHARLES Y. KNIGHT.
